EXCAVATING MACHINE

Glen B. Heffelfinger, Marion, Ohio, assignor to
 The Marion Steam Shovel Company, Marion,
 Ohio, a corporation of Ohio

Application July 23, 1932, Serial No. 624,249

13 Claims. (Cl. 214—135)

This invention relates to an excavating machine and more particularly to means for counterbalancing the weight of the excavating element. It has been proposed heretofore to counterbalance the weight of the excavating element so that little power will be required to elevate the empty excavating element and practically the full power of the hoisting motor may be utilized to pull the excavating element through the bank and to lift the load contained therein, but no satisfactory means has been provided for compensating for the difference between the distance traveled by the excavating element and the distance which is feasible to permit the counterbalancing weight to travel. In the ordinary excavating machine the excavating element is movable from a position adjacent to or below the surface on which the machine rests to a position adjacent to the point of the boom, which is considerably above the superstructure of the machine. The counterweight is connected with the hoisting drum on the platform of the machine and if a single line connection is employed the weight must travel a distance equal to the distance traveled by the excavating element and this would require that the counterweight should be elevated a distance far above the platform, which obviously is undesirable and impracticable. If a multiline connection is employed the counterweight may move a distance less than the distance traveled by the excavating element but the weight must be correspondingly increased.

One object of the present invention is to provide a counterbalancing mechanism of such a character that it will be required to travel a portion only of the distance traveled by the excavating element.

A further object of the invention is to provide such a counterweight mechanism comprising a drum on which the counterweight cable is wound and means connected with the drum to cause the mechanism to travel a distance much less than the length of that portion of the counterweight cable which is wound onto or off the drum.

A further object of the invention is to provide such a counterweight mechanism with automatically controlled means to prevent the same from dropping in the event the counterweight cable breaks or is suddenly slackened off.

Other objects of the invention will appear as the mechanism is described in detail.

In the accompanying drawings Fig. 1 is a side elevation of a conventional excavating machine embodying my invention; Fig. 2 is a transverse sectional view taken on the line 2—2 of Fig. 1 and

partially broken away; Fig. 3 is a side elevation of the counterweight mechanism; Fig. 4 is a rear elevation of the counterweight mechanism, partly in section and partly broken away; and Fig. 5 is a detail view of the locking mechanism.

In these drawings I have illustrated one embodiment of my invention and have shown the same as applied to a power operated shovel of a well known type. It will be understood, however, that this particular embodiment has been chosen for the purposes of illustration only and that the counterweight mechanism may take various forms and may be applied to excavating machines of various kinds without departing from the spirit of the invention.

The power shovel here illustrated is of a conventional design and comprises a platform 6 rotatably mounted on a base 7 which is carried by traction devices 8. A boom 9 extends upwardly and forwardly from the front end of the platform 6 and a dipper arm 10 is pivotally and slidably mounted on the boom between its ends, and has at its outer end an excavating element or dipper 11. A hoisting cable 12 is connected with the dipper and extends about a sheave 13 at the point of the boom and under a guide sheave 14 near the heel of the boom to a hoisting drum 15 on the platform 6. This hoisting drum may be rotated by any suitable mechanism, not shown, such as the usual hoisting motor. An upright frame is mounted on the rear portion of the platform 6 and constitutes a guide along which the counter-weight is moved. Preferably this frame comprises two upright frame members 16 rigidly connected one to the other and braced against lateral displacement, as by laterally extending members or wings 17. The connections between the two frame members are at the forward edges of those members and the space between the frame members is unobstructed and adapted to receive the counterbalancing mechanism. It will be noted that in Figs. 2 and 4 the right hand frame member 16 and adjacent portions of the mechanism are omitted, but these omitted portions are identical with the corresponding portions at the left hand side, as shown in those figures.

The counterbalancing mechanism comprises a weight which may be of any suitable character but is here shown as a receptacle, or box-like structure, 18, adapted to receive heavy material, such as pig iron, scrap iron or the like, in such quantity as will impart thereto the desired weight. Rotatably mounted on the weight box is a drum 19 which is here shown as rigidly secured to a

shaft 20 journaled in bearings 21 mounted on the weight box at the top thereof and preferably arranged at the upper ends of partitions 22 within the weight box. Shafts 23 are journaled in suitable bearings in the partitions 22 and in the side walls of the weight box and are arranged on opposite sides of the drum 19. Each of the shafts 23 has secured to its inner end a gear 24 which meshes with a pinion 25 on the shaft 20. In the present instance, the shafts 23 extend outwardly beyond the respective side walls of the weight box and each has secured to its outer end a pinion 26 which meshes with a rack 27. The racks 27 are rigidly secured to the rear edges of the respective frame members 16, which in the present arrangement are located at opposite sides of the weight box. A cable 28 has one end portion secured to and wound on the counterweight drum 19, extends upwardly and about a sheave 29, supported in an elevated position near the upper ends of the frame members 16, and has its other end connected with the hoisting drum 15 in opposed relation to the hoisting cable 12. As here shown, the counterweight cable 28 is wound on the same drum with the hoisting cable 12 but in the opposite direction. It will be apparent, therefore, that when the dipper is lowered and the hoisting cable unwound from the hoisting drum 15 the counterweight cable will be wound onto the hoisting drum and unwound from the counterweight drum 19 and that the counterweight drum will cause the pinions 26 to rotate in such a direction that they will travel upwardly along the racks 27 and thereby elevate the counterweight mechanism as a whole. Due to the relatively large diameter of the counterweight drum 19 and to the reducing gearing which is interposed between the drum and the pinions 26 the distance traveled by the counterweight mechanism will equal only a small part of the distance traveled by the dipper. When the hoisting drum 15 is actuated to wind the hoisting cable 12 thereon and elevate the dipper the counterweight cable will be unwound from the hoisting drum and the counterweight mechanism permitted to move downwardly by gravity. During this downward movement the pinions 26 will be actuated by the racks 27 to rotate the drum 19 in a direction to wind the cable 28 thereon.

The pinions 26 may be retained in mesh with the racks 25 in any suitable manner but, in the present instance, the frame members 16 are provided with tracks 30 which extend parallel with but in opposed relation to the racks 27, and guide members connected with the weight box travel along these tracks and in such relation thereto as to prevent the pinions moving rearwardly out of mesh with the racks. Preferably a yoke 31 is pivotally mounted on each shaft 23 and extends forwardly beyond the tracks 30. This forwardly extending portion of the yoke has mounted thereon rollers 32 which engage the track 30 above and below the pinion 26. It is desirable that the weight box shall be provided near its lower end with other rollers 33 to engage the tracks 30 and prevent the lower part of the weight box from swinging away from the supporting structure should the frame be inclined rearwardly, as when the machine is supported on an inclined surface. The upright frame is also provided at its forward portion with other tracks, one of which is shown at 34 in Fig. 2, these tracks being arranged near the sides of the weight box and being engaged by rollers 35 secured to the upper and lower portions

of the weight box and here shown as having shafts 36 journaled in bearings 37. These tracks and rollers serve to limit the forward movement of the weight box and to prevent the forward thrust from being imposed upon the racks and pinions. 80 The rollers 35 may be provided with flanges 38 and thus also serve to hold the weight box against lateral movement. Preferably the pinions 26 are so mounted on the weight box that the center of gravity of the latter will be slightly offset from the center in a direction which will cause the weight box to tend to move forwardly by gravity, thus holding the rollers 35 in firm contact with their tracks and preventing any tendency of the weight box to move rearwardly or to sway when the machine is in its normal position. 90

Automatically controlled mechanism is provided to prevent the counterbalancing mechanism from dropping in the event the counterweight cable should break or be suddenly slackened off. This is 95 preferably accomplished by locking the counterweight drum against rotation and thereby holding the pinions against rotation. For this purpose a ratchet wheel is connected with the drum for rotation therewith and a locking pawl cooperates 100 with the ratchet wheel to lock the drum and pinions 26 against rotation in a direction to lower the mechanism. In the construction illustrated an annular member 38a is rigidly secured to the drum and has inwardly extending ratchet teeth 39, there being preferably one of these internal ratchet wheels at each end of the drum. Adjacent to each ratchet wheel a pawl 40 is mounted for movement into and out of engagement with the ratchet wheel. As here shown, this pawl is rigidly secured to a shaft 41 journaled in bearings 42 at the top of the weight box 18. Rigidly connected with the shaft 41 is an arm 43 to the outer end of which is pivotally connected a rod 44 which extends through a guide bracket 45 and is acted 115 upon by a spring 46 confined between the bracket and a suitable stop on the rod, such as a nut 47. Connected with the arm 43 is a second arm 48 which extends upwardly along the counterweight cable 28 and has mounted thereon a grooved roller 49 which engages that cable. The roller 49 is preferably slidably mounted on a shaft 50 and supported at its ends by the arms 48 at the respective sides of the drum, so that it may accommodate itself to the changing position of the cable 125 as the latter is wound onto the drum. The arm 48 is so arranged with relation to the pawl 40 that when the roller 49 is in contact with the cable and the cable is taut the pawl will be held in its retracted or inoperative position, and the spring 130 46 compressed. Should the cable break or become slack the spring 46 will be released and will expand and move the pawl 40 into its operative position, that is, into engagement with a tooth of the ratchet wheel 49, thereby locking the drum 135 against rotation. It is desirable that the arm 48 should be adjustable with relation to the arm 43 and I have therefore shown the arm 48 as loosely mounted on the shaft 41 and connected with the arm 43 by a rod or turn buckle 51 the ends of 140 which are threaded into nuts 52 rotatably mounted in the respective arms.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. A counterbalancing mechanism for the excavating element of an excavating machine, comprising an upright frame mounted on said machine and having rearwardly extending side members provided at their rear edges with toothed racks, oppositely facing tracks arranged in front of and parallel with said racks, a counterweight mounted between said side members and extending rearwardly beyond the same, pinions carried by said counterweight and engaging said racks, a drum rotatably mounted on said counterweight and operatively connected with said pinions, a sheave mounted on the upper portion of said frame, a cable connected with said excavating element, extending about said sheave and wound on said drum to support said counterweight and control the rotation of said pinions, and parts carried by said counterweight and engaging said tracks to control the fore and aft movement of said counterweight. 80
2. A counterbalancing mechanism for the excavating element of an excavating machine, comprising an upright frame mounted on said machine and having rearwardly extending side members provided at their rear edges with toothed racks, said frame also having forwardly facing tracks arranged in front of and parallel with said racks, a counterweight mounted between said side members and extending rearwardly beyond the same, pinions carried by said counterweight and engaging said racks, a drum rotatably mounted on said counterweight and operatively connected with said pinions, a sheave mounted on the upper portion of said frame, a cable connected with said excavating element, extending about said sheave and wound on said drum to support said counterweight and control the rotation of said pinions, members pivotally mounted on said counterweight adjacent to said pinions, and rollers carried by said pivoted members and engaging said tracks to retain said pinions in engagement with said racks. 90
3. A counterbalancing mechanism for the excavating element of an excavating machine, comprising an upright frame mounted on said machine and having rearwardly extending side members provided at their rear edges with toothed racks, oppositely facing tracks arranged in front of and parallel with said racks, a counterweight mounted between said side members and extending rearwardly beyond the same, a drum rotatably mounted on said counterweight and operatively connected with said pinions, a sheave mounted on the upper portion of said frame, a cable connected with said excavating element, extending about said sheave and wound on said drum to support said counterweight, pinions rotatably mounted on said counterweight, engaging the respective racks and operatively connected with said drum, said pinions being so arranged with relation to the center of gravity of said counterweight that the force of gravity will tend normally to move said pinions toward said racks, and means carried by said counterweight and engaging said tracks to limit the swinging movement of said counterweight. 100
4. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported near the upper end of said rack, a cable connected with said excavating element, extending about said sheave and wound on said drum to support said counterweight and control the rotation of said pinion, oppositely facing tracks extending parallel with said rack on that side thereof opposite said pinion, a part carried by said counterweight and engaging one of said tracks to limit the movement of said pinion toward said rack, and a second part carried by said counterweight and engaging the other of said tracks to limit the movement of said pinion in a direction to disengage the same from said rack. 110
5. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave mounted adjacent to the upper end of said rack, a cable connected with said excavating element, extending about said sheave and wound on said drum to support said counterweight and control the rotation of said pinion, a track arranged in opposed relation to said rack on that side thereof opposite said pinion, and a guide member pivotally mounted on said counterweight and having parts engaging said track above and below said pinion to hold the latter in engagement with said rack. 120
6. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported adjacent to the upper end of said rack, a cable extending about said sheave and connected with said drum and said excavating element, a track arranged in opposed relation to said rack, a yoke pivotally mounted on said counterweight and rollers carried by said yoke and engaging said track. 130
7. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported near the upper end of said rack, a cable extending about said sheave and connected with said drum and said excavating element, a track arranged in opposed relation to said rack, a yoke pivotally mounted on said counterweight, rollers carried by said yoke and engaging said track above and below said pinion, and a roller mounted on said counterweight near the lower end thereof and engaging said track. 140
8. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported near the upper end of said rack, a cable connected with said excavating element, extending about said sheave and wound on said drum to support said counterweight and control the rotation of said pinion, oppositely facing tracks extending parallel with said rack on that side thereof opposite said pinion, a part carried by said counterweight and engaging one of said tracks to limit the movement of said pinion toward said rack, and a second part carried by said counterweight and engaging the other of said tracks to limit the movement of said pinion in a direction to disengage the same from said rack. 150

sheave and wound on said drum to support said counterweight, a device carried by said counterweight and movable into and out of a position to lock said pinion and said drum against rotation in a direction to lower said counterweight, and means controlled by said cable to hold said device in an inoperative position when said cable is taut.

9. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported near the upper end of said rack, a cable connected with said excavating element, extending about said sheave and wound on said drum to support said counterweight, a locking device movable into and out of a position to hold said counterweight against downward movement, a member connected with said locking device and normally engaging said cable to hold said locking device in its inoperative position when said cable is taut, and means acting on said locking device to move the same to its operative position when said cable is slack.

10. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported near the upper end of said rack, a cable connected with said excavating element, extending about said sheave and wound on said drum to support said counterweight, a device carried by said counterweight and movable into locking relation to said drum to hold the same against rotation in a direction to lower said counterweight, yieldable means tending to move said device to its operative position, and a part connected with said device and arranged to engage said cable and hold said device in an inoperative position when said cable is taut.

11. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said

counterweight and operatively connected with said pinion, a sheave supported near the upper end of said rack, a cable connected with said excavating element, extending about said sheave and wound on said drum to support said counterweight, a toothed member connected with said drum for rotation therewith, a pawl carried by said counterweight, a spring tending to move said pawl into engagement with said toothed member, an arm connected with said pawl, and a part carried by said arm and engaging said cable to hold said pawl in its retracted position when said cable is taut.

12. A counterbalancing mechanism for the excavating element of an excavating machine, comprising a vertically movable counterweight, a toothed rack supported on said machine adjacent to the path of said counterweight, a pinion rotatably mounted on said counterweight and engaging said rack, a drum rotatably mounted on said counterweight and operatively connected with said pinion, a sheave supported near the upper end of said rack, a cable extending about said sheave and connected with said drum and said excavating element, a toothed member connected with said drum for rotation therewith, a pawl, an arm rigidly connected with said pawl, a spring acting on said arm to move said pawl into engagement with said toothed member, a second arm pivotally mounted on the axis of said pawl, adjustable means for connecting said arms one with the other, and a roller carried by said second arm to engage said cable and hold said pawl against movement by said spring when said cable is taut.

13. A counterbalancing mechanism for the excavating element of an excavating machine, comprising a vertically movable counterweight, a toothed rack supported on said machine adjacent to the path of said counterweight, a pinion rotatably mounted on said counterweight, and engaging said rack, a drum rotatably mounted on said counterweight and operatively connected with said pinion, a sheave supported near the upper end of said rack, a cable connected with said excavating element, extending about said sheave and wound on said drum to support said counterweight, a toothed member, a locking member to engage said toothed member and prevent downward movement of said counterweight, means tending to move said locking member into engagement with said toothed member, and a part connected with said locking member and arranged to engage said cable and hold said locking member out of engagement with said toothed member when said cable is taut.
